UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR PRINTING-TYPES.

Specification forming part of Design No. 7,777, dated September 29, 1874; application filed September 9, 1874.
[Term of Patent 14 years.]

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for Printing-Type, of which the following is a specification:

The nature of my invention is fully shown in the accompanying typographic impression, to which reference is made; and consists of

what I term a script type, ornamented as shown therein.

What I claim as new is—

The design for a font of printing-types, as herein shown.

HERMAN IHLENBURG.

In presence of—

ROBERT R. SMITH,
JOHN A. WOLBERT.
